J. L. MILTON

ELECTRIC SWITCHING DEVICE

Filed April 17, 1922

INVENTOR.
John L. Milton

UNITED STATES PATENT OFFICE.

JOHN L. MILTON, OF LOUISVILLE, KENTUCKY, ASSIGNOR TO CHEATHAM ELECTRIC SWITCHING DEVICE COMPANY, OF LOUISVILLE, KENTUCKY, A CORPORATION OF KENTUCKY.

ELECTRIC SWITCHING DEVICE.

Application filed April 17, 1922. Serial No. 554,299.

To all whom it may concern:

Be it known that I, JOHN L. MILTON, a citizen of the United States, and a resident of Louisville, county of Jefferson, and

5 State of Kentucky, have invented a new and useful Improvement in Electric Switching Devices, of which the following is a specification.

The object of my invention is to provide 10 a solenoid for operating the tongues of switches that will produce a superior draw bar pull within the space available in the present type of devices. A further object is to construct a more durable and less expensive equipment. These and other objects 15 are accomplished by my invention. An embodiment is hereinafter set forth.

For a more complete description of my invention, reference is to be had to the accompanying drawing, forming a part thereof, in which:—

Figure 1 is a view of the complete equipment, partly in cross section and partly in full elevation with parts broken away to 25 show the structure.

Figure 2 is a diagrammatic representation of the application of the coil represented by Figure 1.

In the embodiment of my invention herein 30 represented, a simple non-magnetic tube 1 mounted into a magnetic shell 2, an end piece 3 is in turn tightly mounted into said shell, this structure being so put together that it is hermetically sealed with a view of preventing the ingress of any foreign substance, 4 35 is a plunger which is mounted within the non-magnetic tube 1, 4^a is a magnetic member of this plunger, 4^b is a non-magnetic member, 5 and 6 represent solenoids wound 40 directly on to the tube 1, and properly insulated therefrom in any of the well known methods. 7—8 and 9 represent magnetic washers of sufficient proportion to carry the magnetic flux set up by passing of electric 45 current thru the respective coils 5—6.

As current is sent into the coils 5 or 6 the plunger 4 is actuated. The coils are wound directly on to the central tube which has been previously prepared for mounting into the casing 2 and end 3 together with the insulation and the magnetic members 7—8 and 9. After this has been done the impregnation and surface insulation is added. The solenoid in this complete form is now mounted

into the case 2 and the end member 3 substantially as shown.

In coils of this class as now constructed it is customary to make these coils on bobbins separately and then mount them on to the tube loosely. The means of holding these 60 loosely mounted coils in place has been quite an expense and a problem to make suitable holding devices, such as collars and heavy springs, which apply pressure to the end insulation of said coil. This has lead to 65 trouble from this pressure together with the heating and cooling of the coils which result into expansion and contraction and cause electrical break downs. The novel system 70 set forth above saves very considerable expense, insures an absolute predetermined alignment of the coils and eliminates a large 75 part of the air space between the inner convolutions of the coil and the plunger, thereby making a very superior coil which increases the effective draw bar pull of the plunger approximately 47%.

The magnetic shell 2 with its end pieces 3 forms a cylinder which is in its completed 80 form mounted into what is known in the art as a ground box, linkage as shown in Figure 1 and 2 are employed to connect the plunger 85 to the tongue of the switch so that it will operate from one position to another according to whether coil 5 or 6 is energized.

While other detailed embodiments of this invention may be made it is obvious that it is not restricted thereto, and I do not limit myself to the structure as shown. I wish to 90 cover the scope of this invention according to the annexed claims.

I claim:—

1. In an electromagnet, comprising a magnetic plunger, a magnetic cylinder shell included in the magnetic path of the flux of 95 said electromagnet, a central non-magnetic tube mounted therein and sealed in the ends of said shell with closures, two adjacent similar windings disposed directly on said tube and pole pieces disposed on said tube, between and at the ends of said coils and out 100 of contact magnetically and structurally with the shell, said tube having an open end through which passes a non-magnetic connection from the plunger to the device to be 105 operated.

2. In an electromagnet, comprising a magnetic plunger, a magnetic cylinder shell in-

cluded in the magnetic path for the flux of said electromagnet, a central non-magnetic tube mounted therein and sealed in the ends of said shell with closures, two adjacent similar windings disposed directly on said tube and pole pieces disposed directly on said tube, between and at the ends of said coils and out of contact magnetically and structurally with the shell, the assembly of the

coils and pole pieces being much shorter than the shell, said tube having an open end through which passes a connection from the plunger to the device to be operated.

In testimony whereof, I have hereunto set my hand and seal this 15th day of April, 1922.

JOHN L. MILTON.
